UNITED STATES PATENT OFFICE.

JOHN W. GRAHAM, OF HINTON, WEST VIRGINIA.

TYPOGRAPHICAL OR SLUG CASTING MACHINE.

1,235,563.

Specification of Letters Patent. Patented Aug. 7, 1917.

Application filed May 3, 1915. Serial No. 25,510.

To all whom it may concern:

Be it known that I, JOHN W. GRAHAM, a citizen of the United States, residing at Hinton, in the county of Summers and State 5 of West Virginia, have invented certain new and useful Improvements in Typographical or Slug Casting Machines, of which the following is a specification.

My invention relates to typographical or 10 slug casting machines, such as linotypes or the original construction; wherein, circulating matrices are released from a magazine in the order in which their characters are to appear in print, and then assembled in line 15 together with expanding spacers; the composed line brought in contact with the face of a mold; the mold filled with molten metal to form a line of type or slug against the matrices, which produce the type characters 20 thereon, and the matrices thereafter returned to the magazine from which they were originally drawn.

More particularly it relates to that class 25 of machines having a series of magazines, any one of which can be shifted into operative position, and wherein; the magazines are individually removable and exchangeable, and, to that end are mounted in a basket or rack support; and wherein, each 30 magazine is provided with an individual escapement mechanism consisting of verges and a slotted bar in which the verges are housed; and such escapement mechanism is made fast to the magazine.

35 In the drawings I have shown the invention as applied to linotype machines, but obviously, it may be applied to other machines, such as typesetters, and typecasters, and many changes and variations may be 40 made therein, without departing from the spirit of the invention or the principle thereof.

Generally speaking I desire to be understood that I do not limit myself to any specific form or embodiment, except in so far as such limitations are specified in the claims.

Referring to the drawings, Figure 1 is a side view of a portion of a linotype machine having my invention applied thereto. Fig. 50 2 is a frontal and side elevation view of the cog gear and worm gear A³. Fig. 3 is a view of the rollers, cogs and sprocket, that are used in the power raising and lowering device. Fig. 4 is a back view of the supporting frame or arm which supports the 55 rack or basket, showing part of the mecha-

nism for raising and lowering the basket or rack. Fig. 5 is a side view of a section of rack or basket showing the escapement mechanism. Fig. 6 is a side view of the key board mechanism. Fig. 7 is a view of a magazine looking at the bottom, showing the bar to house the verges and also the strengthening bars. Fig. 8 is a perspective view of a section of a magazine resting on its angle iron support and showing the dog, which holds the magazine in place. Fig. 9 is a rear view of a basket.

Referring to Fig. 1

A represents a side view of the main arm 70 or frame which supports the basket or rack. This arm is formed in the arc of a circle, and the basket or rack which travels on this arm, travels with a circular motion. The basket, at the front and rear ends, the 75 arm A, and the guide plates B³, are all formed in the arcs of circles, such circles having a common center; thus the motion of the basket is the same as if it were connected to a positive center, which positive center would be situated at a point sufficiently forward to be a common center for all of these circles, but, by suspending the basket to the arm A, we accomplish the desired result without putting any 80 of the mechanism in the way of the operator. It is also apparent to those skilled in the art, that the front and rear ends of the magazines come into operative position 85 at the same time.

A¹ represents an arm attached to the main arm A, at each side and extending back to support the distributing mechanism, this arm is offset at its point of connection with the arm A, to allow the piece B² to pass behind it.

A² represents a cog gear immediately behind the worm gear wheel, A³. (See Fig. 2.) The gear wheel A² carries the piece B².

A³ represents a worm gear wheel intermeshing with the worm thread on the shaft A⁴.

A⁴ represents a shaft having at its uppermost end a worm thread, and at its lower end a bevel gear.

A⁵ represents a brace to strengthen the main arm A. There are two of these braces, one at each side of the forked arm A.

B represents the basket or rack, in which the magazines are housed.

B¹ represents the iron straps which pass up the sides of the basket at its ends, and

to which the individual baskets are made fast; these straps also rub on the inside of the arms A, and the braces A⁵; to guide the travel of the basket.

5 B² represents a strap which travels on the cog gear A², and is bolted to the guide bar B³.

B³ represents the guide bars which are securely affixed to the basket and travel on 10 the main arm A. These guide bars B³ are bored out near their ends, and have housed in these sockets, the rollers B⁴.

B⁴ represents rollers set in guide bars, as mentioned above.

15 B⁵ represents an angle iron, one side of which is affixed securely to the straps B¹ at both ends of the basket, and to the guide bars B³ near the center of the basket; the other angle of this angle iron projects into 20 the inside of the basket, at right angles, thus forming the support for the magazines. These angle irons on the inside of the basket work in pairs, one on each side, and are lined on their bottom, full length, thus giving the 25 basket the appearance of a box containing a series of shelves, all converging toward their frontal point, at the same degree. The object of this lining is to support the magazine when it is pulled back, to be taken out. The 30 magazine being narrower at its frontal end than at its rear end, would drop through at the back, but for this lining. This lining is shown by the line B¹⁰, in Figs. 8 and 9.

B⁶ represents a dog fitted on the inside 35 of the angle irons B⁵, near the lower, or escutcheon end of the basket. Its function is to hold the magazine in place. Its construction is such as to hold the magazine from slipping endwise in the basket and it 40 also holds the magazine down in place. (See Fig. 8.)

Fig. 2 shows front and side elevation views of the cog gear A², and its connected worm gear wheel A³.

45 Fig. 3 shows the rollers, gears and sprocket of the power raising mechanism, with the casting Z removed.

D represents a roller set stationary below the belt E. Its function is to hold the belt E 50 up in place when the rollers F or G are thrown against the belt E, to operate the power raising or lowering device.

E represents the belt from which power is generated to operate the power raising and 55 lowering device.

F represents the rubber covered roller of sufficient width to cover the width of the belt E and having behind, and made fast to it, the cog gear F¹.

60 G and G¹ are exact duplicates of F and F¹.

I represents a cog gear, made fast to the sprocket J and of a width the same as F¹ and G¹.

65 J represents the sprocket mentioned above.

Z represents the casting which houses the rollers, gears and sprocket used in the power raising device. It is pivoted on the pin Z¹, which is set securely in the frame of the machine. It is connected at its uppermost 70 end to the strap L¹, which in turn is connected to the lever L. The rollers F and G with their connected cog gears F¹ and G¹ are housed on pins made fast to the casting Z, while the sprocket J and its attached gear 75 wheel I are housed on the pin Z¹. The gear wheel G¹ is intermeshed with the gear wheel F¹ and the gear wheel F¹ also intermeshes with the gear I, but the gear G¹ does not intermesh with the gear I. 80

In operating the power mechanism, when the lever L is moved inward sufficiently it rocks the casting Z on the pivot Z¹ and forces the roller G against the moving belt E, which belt E operates the roller G and its connected gear wheel G¹. G¹ is intermeshed with F¹ and thus operates it. F¹ is intermeshed with the gear I, made fast to the sprocket J, and thus the sprocket J is operated. The sprocket J operates the shaft 90 K¹, by the sprocket chain M and the sprocket K, on the shaft K¹. The shaft K¹ operates the screw shafts A⁴, by means of intermeshed bevel gears and the shafts A⁴ operate the worm gear wheels A³ and their attached cog 95 gears A², thus operating the basket upward or downward by means of the piece B². To reverse this motion the hand lever L, is moved outward sufficiently to throw the roller F against the belt E and this operates the roller F and its attached gear F¹. F¹ operates the gear I being intermeshed with it and I being fast to the sprocket J operates it, and the power is transmitted as above. Fig. 4 represents a back view of the 100 forked arm A. This view shows the shaft K¹ with its sprocket and bevel gears and the screw shafts A⁴, attached to the arm A. 105

Fig. 5 is a side view of a section of a basket with a section of the strap B¹ cut away; also a section of angle iron magazine support B⁵ cut away; also section of the side of the magazine cut away to show the matrices X in place, held by the verge V; also shows the reinforcing bar W¹, slotted to receive the spring P, and also shows trip finger Q, connected to the key rod Q¹. 110

Fig. 6 shows a side view of the key board mechanism.

Q² represents a key.

Q³ shows key bar.

Q⁴ shows pin on which key bar is pivoted.

Q⁵ shows rod to trip the dog R.

R¹ shows leg of the dog R.

R² shows rod housing the cam R³.

R⁴ shows rubber covered rollers.

R⁵ shows spring to hold key rod down.

In operation, when the key Q² is pressed it raises the rod Q⁵, which moves the dog R and allows the leg R¹ to pass into the slot 130

in the rod R^2 , thus allowing the rod R^2 to drop. The key rod Q^1 being pulled down by the spring R^5 , immediately drops. This operates the trip finger Q , causing it to trip the verge V , thus allowing the matrix X to escape. This reverses to a considerable extent the key board action of other machines. The usual way is to suspend the key rod Q^1 at a slight distance above the rod R^2 , and not resting on it as in my machine. When the key Q^2 is pressed it raises the rod Q^5 , in turn operating the dog R , allowing the rod R^2 to drop, but the key rod Q^1 does not drop, but being suspended above the rod R^2 , it remains stationary. When the rod R^2 drops, the cam R^3 comes in contact with the moving roller R^4 , and when the cam rolls over to its highest point it raises the rod R^2 sufficiently to raise the key rod Q^1 , and the key rod comes in contact with the verge V and trips it, allowing the matrix to escape. In my machine as soon as the key is touched the key rod drops and trips the verge, allowing escapement of the matrix and as the mechanism is moving to restore the rod Q^1 to its place, the operator may be touching another key and no time is lost. Operators listen at all times to hear the matrices drop, so by the old method the operator has to wait until the operation of key board mechanism is complete, before he hears the matrix drop, while in my machine the matrix drops almost instantaneously and the operator can operate another key while the mechanism is readjusting itself. This improvement greatly increases the speed of the machine.

Fig. 7 shows bottom view of a magazine showing strengthening bars W^1 , extended out at their ends to act as stop, working in conjunction with the dog B^6 , (see Fig. 8).

Fig. 8 shows a perspective view of a section of magazine, showing angle iron supports cut away to show the extended end of the strengthening bar W^1 , and also the dog B^6 , dotted in.

Fig. 9 shows a back view of the basket, showing the sheet iron lining.

Having described my invention, its construction and operation, what I claim and desire to secure by Letters Patent of the United States, is as follows:

1. In a typographical machine the combination of a basket to house a plurality of magazines, means for moving the basket up and down, said basket made in the general shape of a truncated wedge and having both its ends formed in the arcs of circles, a forked arm made in the form of an arc of a circle, and guide bars affixed to the basket so shaped as to guide the travel of the basket upward and downward on the arm A , with a circular motion.

2. In a typographical machine the combination of a basket to house a plurality of

magazines, said basket made in the general shape of a truncated wedge and having both its ends formed in the arcs of circles, a forked arm made in the form of an arc of a circle, and guide bars affixed to the basket and so shaped as to guide the travel of the basket upward or downward on the arm A , with a circular motion, and the circles upon which the front and back ends of the basket, the arm A , and the guide bars B^3 , are laid out, having a common center, and the lines at which the individual baskets or magazines rest all being laid out at the same degree from such common center, thus enabling the basket in its line of travel to arrive with both its ends, in operative position at the same time, without any devices being added to the ordinary escapement channel or channel entrance.

3. In a typographical machine the combination of a basket to house a plurality of magazines, said basket made in the general shape of a truncated wedge and having both ends formed in the arcs of circles, a forked arm made in the form of an arc of a circle, and guide bars affixed to the basket and so shaped as to guide the travel of the basket upward or downward on said forked arm with a circular motion, and means for raising and lowering said basket consisting of normally idle rollers, a moving belt, means whereby the idle rollers may be brought in contact with the moving belt and means to transmit the motion to the basket to raise or lower it.

4. In a typographical machine the combination of a plurality of removable magazines, and a rack to house the said magazines, said rack being made in the form of a truncated wedge, whereby the magazines are closer together at their front end than at their rear end and means engaging said rack intermediate its ends for moving the same bodily in the arc of a circle whereby the magazines may be brought into alinement with a single pair of entrance and exit channels.

5. In a typographical machine the combination of a plurality of removable magazines, and a rack to house the said magazines, said rack being made in the form of a truncated wedge, whereby the magazines are closer together at their front end than at their rear end, with their front ends forming a concave arc and their rear ends forming a convex arc.

6. In a typographical machine, the combination of a plurality of removable magazines, common entrance and exit channels for said magazines, a movable rack to house said magazines being made in the form of a truncated wedge, guide bars associated with said rack adapted to aid in insuring movement in a predetermined direction, and means for moving said rack bodily in the

arc of a circle whereby the magazines may be brought into alinement with said common entrance and exit channels.

7. In a typographical machine the combination of a plurality of removable magazines, a rack to house the said magazines being made in the form of a truncated wedge, guide bars affixed to the said rack, and a sector having a cogged surface affixed 10 to one of said guide bars on each side of the said rack.

8. In a typographical machine the combination of a plurality of removable magazines, a rack to house the said magazines 15 being made in the form of a truncated wedge, guide bars affixed to the said rack, a sector having a cogged surface affixed to one of said guide bars on each side of the said rack, and a forked arm made in the arc of a 20 circle coacting with said guide bars.

9. In a typographical machine the combination of a plurality of removable magazines, a rack to house the said magazines being made in the form of a truncated 25 wedge, guide bars affixed to the said rack, a sector having a cogged surface affixed to one of said guide bars on each side of the said rack, a forked arm made in the arc of a circle coacting with said guide bars, and a 30 cog wheel affixed to each fork of said forked arm and intermeshing with the said cogged sector.

10. In a typographical machine the combination of a plurality of removable magazines, a rack to house the said magazines 35 being made in the form of a truncated wedge, guide bars affixed to said rack, a sector having a cog surface affixed to one of the said guide bars on each side of the said rack, a forked arm made in the arc of a 40 circle coacting with said guide bars, a cog wheel affixed to each fork of said forked arm and intermeshing with the said cogged sector, manually operated means to simultaneously operate the said cog wheels in 45 either direction to shift the said rack, a power shifting mechanism including a normally moving belt, and two normally idle rollers having intermeshing cog gears, a cog gear intermeshing with the attached cog gear on one of the said rollers, a casting housing the said rollers and cog gears, a pin 50 on which said casting rocks, means to rock the said casting to bring either one of the said rollers in contact with said moving belt, and means to transmit the motion to the said cog wheels on the forked arm and thereby shift the magazines.

In testimony whereof I affix my signature in presence of two witnesses.

JOHN W. GRAHAM.
